(57) **CLAIM**

The ornamental design for a flexible compact display stand, as shown and described.

DESCRIPTION

FIG. 1 is a front view showing our new design in a flat position, the rear view being identical thereto;

FIG. 2 is a front perspective view of the design shown in FIG. 1 in a curved position for receiving a display item;

FIG. 3 is a rear left side perspective view of the design shown in FIG. 1 in a curved position for receiving a display item;

FIG. 4 is a right side perspective view of the design shown in FIG. 1 in a curved position for receiving a display item;

FIG. 5 is a left side perspective view of the design shown in FIG. 1 in a curved position for receiving a display item;

FIG. 6 is a top perspective view of the design shown in FIG. 1 in a curved position for receiving a display item;

FIG. 7 is a bottom perspective view of the design shown in FIG. 1 in a curved position for receiving a display item;

FIG. 8 is a right side environmental perspective view of the design shown in FIG. 1 with a mounted display item; and,

FIG. 9 is a rear left side environmental perspective view of the design shown in FIG. 1 with a mounted display item.

The broken line showing of a mounted display item in FIGS. 8 and 9 is for the purpose of illustrating an environmental structure and forms no part of the claimed design.
